UNITED STATES PATENT OFFICE

2,286,657

BLACK-OUT LAMP

Kenneth P. Swanson, North Valley Stream, Long Island, N. Y., assignor to Wabash Appliance Corporation, Brooklyn, N. Y., a corporation of New York

Application February 9, 1942, Serial No. 430,007

3 Claims. (Cl. 176—34)

The present invention consists in a new and improved blackout lamp for use under war-time conditions where it is essential to provide a reliable source of dimmed or colored light with positive assurance that no light of a different character shall escape. The blackout light of my invention fulfills these conditions and has other desirable features. As herein shown it comprises a bulb having a defined area of limited extent that may be set off for special treatment in the 10 bulb in accordance with the color or intensity of the light which it is desired to transmit. For example, the bulb may be shaped to include a projecting cylindrical portion of reduced diameter terminating in a curved circular end wall and this cylindrical portion or its end wall is thus conveniently located and disposed for treatment by dipping, spraying or otherwise to determine and establish its light-transmitting properties.

As herein shown and as another desirable feature, there is preferably employed in the lamp of my invention a bulb provided with an inner or inwardly directed metallic reflecting coating which not only prevents the escape of light rays through the body of the bulb, but concentrates and directs the light of the filament to the colored or partially obscured transmitting area. While the reflecting coating may in some instances be by itself effective as a complete light screen I prefer to supplement it by an exterior coating or film of an opaque heat-resisting character. This may be disposed co-extensive with respect to the inner reflecting surface and may extend from the base of the lamp to the boundary of the treated light-transmitting portion of the bulb. The lamp of my invention is thus efficient, has proved durable in use and may be placed in light sockets already available on commercial service circuits.

These and other features of the invention will be best understood and appreciated from the following description of a preferred embodiment thereof, selected for purposes of illustration and shown in the accompanying drawing in which,—

Fig. 1 is a view of the lamp in elevation.

Fig. 2 is a view in partial longitudinal section, and

Fig. 3 is a fragmentary view, partially in cross section, showing the various coatings on the bulb in exaggerated thickness.

The bulb herein shown has a main glass body portion 10 with side walls which are approximately cylindrical but diverge outwardly from the base to a slight degree and then merge through an inwardly curved annular shoulder 58 into a short cylindrical portion 11 of reduced diameter as compared to the rest of the bulb. The cylindrical portion 11 of the bulb terminates in a curved end wall 12 of flattened convexity. 5 The bulb has the usual threaded metallic base 13 and center terminal 14 which together provide terminals for the filament circuit. The bulb is provided with a mount and filament 15 of any usual or conventional character.

The inner wall of the bulb is provided with a metallic coating 16 of aluminum or silver which extends continuously from the base up to a circumferential line defining the end wall area of the bulb. The reflecting coating may be applied to the inner bulb surface by any of the several available commercial processes; for example, by that disclosed in U. S. Letters Patent No. 2,193,555, granted March 12, 1940, to Birdseye Electric Corporation. In accordance with that patent the inverted lamp bulb may be partially filled with a silver depositing solution that is caused to flow continuously over the glass surface until a continuous silver coating has been deposited on the glass. This has a high light reflecting efficiency and is also substantially impervious to the passage of light rays.

The convex end wall 12 of the projecting cylindrical portion 11 of the bulb is then provided with a coating of translucent, heat resistant 30 solution, for example, sodium silicate carrying a blue or red or other colored pigment. The lamp is completed by providing the exterior surface of the body 10 with a similar coating of black color which extends from the base up to the circumferential line of colored coating upon the convex end wall of the bulb. This exterior coating supplements the internal reflecting coating of the bulb body, thus rendering it completely impervious to the passage of light rays. The boundary 35 of the colored coating is herein shown as located somewhat below the edge of the circular end wall 12 of the cylindrical portion 11 so that a short portion of the cylindrical wall is included in the light-transmitting area of the lamp, but 40 the exact location of this boundary line is not important so long as the entire end wall is included. However, for convenience in spraying it is desirable that the boundary line of the translucent area should lie in a cylindrical portion of the bulb. It will be noted that practically the entire bulb surface except its light transmitting area is provided with two light-confining coatings, the inner reflecting coating and the outer black coating. 45 This feature contributes to the production

at moderate cost of a successful blackout lamp since the two coatings supplement each other, one covering any defect that may occur in the other. The manufacturing requirements are thus relaxed and a structure provided that may be produced advantageously under available facilities. In a broad aspect my invention contemplates the employment of two supplementary light-confining coatings of any suitable character in a bulb of any shape commercially available, although it is desirable that the inner coating should be of a reflecting character as the lighting efficiency of the lamp is thereby improved.

It is preferred to employ a solution of sodium silicate with a black or colored pigment for the coating material since this is heat-resistant and is not impaired by the heat of the lamp even in long periods of continuous use. Moreover, it may be sprayed directly upon the warmed bulb of the lamp and quickly dried and baked thus providing a permanent, vapor-free coating. Two or more coatings may be applied to the bulb if desired, although as a general thing the employment of a metallic coating with a single 25 external silicate coating results in a bulb which is opaque in its areas of superposed coatings.

When a bulb provided with an internal reflecting surface is used the entire luminous energy of the lamp is directed through the colored or partially obscured light-transmitting end wall and the latter is caused to glow vigorously with an intense blue or red light which while useful within a short range, is not visible at any substantial distance.

The lamp of my invention has been found entirely satisfactory in use, being durable, efficient, pleasing in appearance, and providing a limited source of blue or red light rays of an intensity which may be readily controlled by varying the thickness of the colored coating upon the circular convex end wall of the lamp.

Having thus disclosed my invention and described one illustrative embodiment thereof, I

claim as new and desire to secure by Letters Patent:

1. An electric incandescent blackout lamp comprising a bulb having a main body portion and a projecting portion of reduced diameter terminating in a circular convex end wall, a filament in the bulb, a substantially opaque metallic reflecting coating on the body of the bulb for directing rays from the filament into the projecting portion of the bulb, and a colored translucent heat-resistant coating covering at least the circular end wall of said reduced portion.

2. An electric incandescent blackout lamp comprising a bulb having a filament-containing body portion defined by approximately cylindrical but slightly divergent side walls, the latter merging through a convex annular shoulder into a short cylindrical portion of reduced diameter terminating in a circular convex end wall, the body portion being provided internally with a substantially opaque metallic reflecting coating and externally with a substantially opaque coating of a black pigment in sodium silicate, the said coatings terminating substantially together in a boundary line extending about the short cylindrical portion of the bulb, and the remainder of said short cylindrical portion, including its end wall, having an external, heat-resisting pigmented translucent coating.

3. An electric incandescent blackout lamp comprising a bulb having a base and a filament-containing body portion defined by approximately cylindrical but slightly flaring side walls, the latter merging into a short cylindrical portion of reduced diameter terminating in a circular convex end wall, said short cylindrical portion having on at least its said end wall an external heat-resisting pigmented translucent coating, and said body portion having an internal metallic reflecting coating and an external opaque heat-resisting coating which extend from the base extensively to the boundary line of said pigmented coating in the said short cylindrical portion of the bulb.

KENNETH P. SWANSON.
